UNITED STATES PATENT OFFICE.

NATHANIEL S. MONROE, OF ARTHUR, ILLINOIS.

ROAD-WORKING MACHINE.

1,131,409.

Specification of Letters Patent.

Patented Mar. 9, 1915.

Application filed March 12, 1914. Serial No. 824,162.

To all whom it may concern:

Be it known that I, NATHANIEL S. MONROE, a citizen of the United States, residing at Arthur, in the county of Douglas and State of Illinois, have invented certain new and useful Improvements in Road-Working Machines, of which the following is a specification.

This invention relates to road working machines, and it has particular reference to that type of machines which are shown in several patents issued to me, for instance, Patent No. 1,015,820, dated Jan. 30, 1912, said machine comprising rearwardly divergent scraper bars which are adjustably supported from a wheeled frame.

The present invention has for its object to provide simple and convenient means for smoothing and compacting material issuing between the spaced rear ends of the scraper bars, said smoothing and compacting means being of a width to cover a swath or track considerably in excess of the distance between the rear ends of the scraper bars, so that the smoothing and compacting action will be applied to a considerable portion of the width of the road which will thus be crowned and smoothed in a very perfect manner.

A further object of the invention is to improve the manner of connecting the smoothing and packing element with the frame of the machine in such a manner that it will not be susceptible of lateral movement except by positive adjustment but means being provided for the vertical adjustment of said smoothing and packing element to determine the force with which said element shall impinge on the road surface.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood

that no limitation is necessarily made to the precise structural details therein exhibited, but that changes, alterations and modifications within the scope of the claims may be resorted to when desired.

In the drawings.—Figure 1 is a side elevation of a road machine to which the invention has been applied. Fig. 2 is a top plan view of the rearward portion of said machine, with dotted lines showing a different adjustment of the smoothing and compacting device. Fig. 3 is a perspective detail view showing the rearward end of one of the frame bars of the machine and a washer applied thereto. Fig. 4 is a perspective detail view showing the forward end of one of the side bars or members carrying the smoothing and compacting element. Fig. 5 is a detail side view illustrating a modification.

Corresponding parts in the several figures are denoted by like characters of reference.

The frame of the machine to which the present invention is applied is supported on wheels 15, and said frame includes rearwardly divergent frame bars 16. Rearwardly convergent scraper bars 17 are adjustably supported by means including supporting and hoisting tackle, substantially as shown, but which is not herein claimed and which does not require to be described in detail.

The present invention includes a smoothing and compacting element which has been shown as consisting of a channel bar 18 which is supported and carried by a pair of angle bars 19 with which it is securely connected in any convenient manner, braces 20 and 21 being utilized to reinforce the construction, the object being to produce a perfectly rigid structure embodying the smoothing and packing element 18 and the supporting bars 19. The latter are pivotally connected with the side bars 16 of the frame near the rear ends of said side bars by means of bolts 22 for the reception of which each supporting bar 19 is provided with a plurality of apertures 23, as clearly seen in Fig. 4 of the drawings. It will thus be seen that

adjustment may be effected to present the smoothing and packing element 18 obliquely with respect to the frame of the machine, as clearly seen in dotted lines in Fig. 2 of the drawings. To enable such adjustment to be conveniently made, it may be found desirable to use convex washers 24 to space the forward ends of the supporting bars 19 outwardly from the rear ends of the frame bars 16, as shown.

For the purpose of effecting vertical adjustment of the smoothing and packing element, the latter is connected by a flexible connection 25 passing over a guide element, such as a pulley 26 supported on the frame of the machine with a drum 27 on a shaft 28 operable by means of a hand wheel 29. The flexible element may include a rod 30 which is less expensive than a chain and less liable to become tangled. By this simple mechanism the smoothing and packing element may be raised from the ground, as seen in dotted lines in Fig. 1, or it may be lowered so as to impinge on the surface of the ground with varying degrees of pressure, it being evident that by tensioning the flexible element 25, the pressure on the surface engaged by the smoothing and packing element may be relieved.

Under the slightly modified construction illustrated in Fig. 5, the guide pulley 26 is replaced by a bell crank 35, one arm of which is connected by a flexible element 36 with the smoothing and packing element, the other arm of the bell crank being connected with means whereby it may be tilted or actuated, as will be readily understood, no limitation being made to any specific lifting means for the smoothing and packing element.

In machines of this class it has been customary to employ a drag, flexibly connected with the frame of the machine for the purpose of engaging the material issuing between the convergent rear ends of the scraper bars. A drag thus mounted or connected is liable to lateral displacement, especially when working on slanting surfaces, and when it is necessary to turn the machine around such drags have been found to be obstructive and cumbersome. By the present invention the smoothing and packing element is spaced from the rear ends of the scraper bars, but it is supported rigidly with respect to the frame of the machine of which it may be regarded as constituting a part. It follows that when the said element has been adjusted to such position as is regarded particularly desirable for the work at hand, it will remain in such position regardless of the movement of the machine with which it is connected. Thus, when it is desired to present the smoothing and packing element obliquely with respect to the machine for

the purpose of causing the material engaged to move laterally in one direction, such position will be securely maintained, while on the other hand the smoothing and packing element may be presented transversely in the path of the material issuing between the scraper bars and maintained securely in such position when desired. The presence of the plurality of the bolt receiving apertures 23 in the supporting bars 19 also enables the distance between the smoothing and packing element and the rear ends of the scraper bars to be varied when desired.

Having thus described the invention, what is claimed as new, is:—

1. The combination with a road machine of the character described and including a wheel supported frame having side members and rearwardly convergent scraper bars supported by said frame, of a drag comprising a transverse trowel bar constituting a smoothing and packing element and rigid supporting bars rigidly connected with said trowel bar adjacent to the ends thereof, and means for connecting the forward ends of the supporting bars with the side members of the frame to maintain the trowel bar in earth engaging position to the rearward of the scraper bars.

2. The combination with a road machine of the character described and including a wheel supported frame having side members and rearwardly convergent scraper bars supported by said frame, of a drag comprising a transverse trowel bar constituting a smoothing and packing element and rigid supporting bars rigidly connected with said trowel bar adjacent to the ends thereof, means for pivotally connecting the forward ends of the supporting bars with the frame to maintain the trowel bar in earth engaging position to the rearward of the scraper bars, and means for lifting the trowel bar from engagement with the ground.

3. In a road machine, a wheel supported frame having side bars, rearwardly convergent scraper bars supported by the frame, a smoothing and packing element, rigid supporting bars with which said element is rigidly connected, and means for adjustably connecting the supporting bars with the frame of the machine to permit the smoothing and packing element to be positioned at various angles, transversely, with respect to the frame.

4. In a road machine, a wheel supported frame having side bars, rearwardly convergent scraper bars carried by the frame, a smoothing and packing element comprising a bar member positioned transversely in rear of the frame, means for connecting said bar member with the frame including rigid supporting bars, bolts connecting said bars pivotally and adjustably with the side bars

of the frame, and convex washers interposed between the frame bars and the supporting bars, and adjusting means for the smoothing and compacting element whereby said element may be supported in the path of material issuing between the rearward ends of the scraper bars.

Copies of this patent may be obtained for five cents each, by addressing the "Commissioner of Patents, Washington, D. C."

In testimony whereof I affix my signature in presence of two witnesses.

NATHANIEL S. MONROE.
